UNITED STATES PATENT OFFICE.

MARTIN E. HERSEY, OF HARRISBURG, PENNSYLVANIA.

STEAM-BOILER SETTING.

SPECIFICATION forming part of Letters Patent No. 392,428, dated November 6, 1888.

Application filed May 31, 1888. Serial No. 275,610. (No model.)

To all whom it may concern:

Be it known that I, MARTIN E. HERSEY, of Harrisburg, in the county of Dauphin and State of Pennsylvania, have invented certain new and useful Improvements in Steam-Boiler Settings; and I do hereby declare the following to be a full, clear, and exact description of the same, reference being had to the accompanying drawings, forming a part of this specification, and to the figures and letters of reference marked thereon.

The present invention has for its object to so construct a boiler-setting as that complete combustion is secured without the necessity of a forced draft, the parts being rendered much more durable than the ordinary setting, not liable to be clogged with dirt or broken while in use, and withal so constructed as that ready access may be had to all parts of the boiler for inspection or repair without destroying the setting.

To these ends the invention consists in certain novel features of construction and combinations and arrangements of parts to be hereinafter described, and pointed out particularly in the claims at the end of this specification.

In the accompanying drawings, Figure 1 is a longitudinal vertical section through a boiler-setting constructed in accordance with my invention. Fig. 2 is a section on the line $x-x$, Fig. 1. Fig. 3 is a section taken horizontally through the bridge-wall. Fig. 4 is a longitudinal vertical section of the bridge-wall. Fig. 5 is a view of a modification.

Similar letters of reference in the several figures indicate the same parts.

The boiler-setting to which my invention is particularly applicable is that commonly known as the "Weitmeyer setting," in which the larger part of the air for supporting combustion is taken in at the rear end and caused to impinge on a flame-bed, A, underlying the rear end of the boiler, before reaching the ash-pit, from whence it is distributed to the grate-surface. The flame-bed A referred to extends rearwardly from the bridge-wall, and I preferably construct it of rectangular blocks of fire-brick, a, supported on the flanges of inverted T-shaped girders B, passing from side to side of the setting, the ends of the girders being

supported on ledges b, formed by building a thin wall to the required height inside the regular solid setting-walls C, or else by making bracket-ledges on said walls, as will be readily understood. The flanges of the T-shaped girders are located at the bottom, thus insuring the proper positioning of the refractory blocks, but more particularly to prevent the exposure of much if any of the iron surface to the action of the flame, and at the same time present a relatively large radiating-surface for heating the air passing through the flue beneath.

To supply air to the top of the bridge-wall D and cause the complete combustion of the gases passing off from the fire, I form flues d, extending diagonally upward from the ash-pit, and over the upper ends of these flues locate suitable hollow fire-bricks with small perforations therein, the interior cavities in such bricks being of considerably greater area than the cross-sectional area of the supply-flues, thus forming expansion-chambers in which the air is highly heated before passing out to commingle with the products of combustion.

The expansion-chamber may be continuous from one end of the bridge-wall to the other and formed of a single fire-brick of inverted-V shape or semicircular; or it may be divided into a number of separate chambers formed by independent bricks of substantially the same shape as shown.

The flues are formed by a series of castings, E, having the broad flat or flanged bases e, which rest on the inclined face of the bridge-wall, and the narrow flat or flanged top E', connected to the base by the webs e², forming the divisions between the flues. The tops E' support the rectangular fire-bricks F, constituting the outside of the flues. The end bar, G, for supporting the rear ends of the grate-bars, also serves as a support for the castings and fire-brick forming the flues d, being constructed for the purpose with the two rails g¹ and g², the former serving to support the ends of the grate-bars and the latter the bases of the castings E, the webs g², connecting the two rails, being preferably so located as to fall in line with the division between the flues, air, of course, being admitted to the flues through the openings in the end bar.

In order that no dirt or soot shall lodge in the flues *d*, the top and bottom of the castings *E* converge as they near the top, forming tapering flues opening out into the expansion-chambers, as before explained. Thus any dirt or soot will, when it enters said flues, at once fall clear through into the ash-pit.

As before explained, the ash-pit is supplied with air taken in from the rear end and carried through the bridge-wall, a suitable steam-supply being located in the ash-pit, if desired, and an additional air-supply at the forward end, the air entering through the latter being heated by being passed around through the casing of the fire-door, which for this purpose is made hollow, as shown, either by being cast in such form or by making the casing of two concentric rings, one smaller than the other, the whole being embedded in the wall of the setting independent of the boiler and readily removable for repair or renewal. The hollow casing may be thick enough to extend below the end bar, *H*, and have the exit-apertures open directly into the ash-pit, although I prefer to form apertures in the dead-plate and run air-passages *I* down into the ash-pit, as shown, the air-inlet passages *K* being always located at the top of the casing on the outside, thus keeping up a constant circulation of air around in the casing from top to bottom, keeping it at all times cool, and at the same time effectually heating the air entering the ash-pit from the front.

It is obvious that the castings forming the flue *d* may be made in a single piece, if desired, or as shown in Fig. 5, and that the form of the same may be varied considerably without departing from the spirit of my invention.

40 The advantages will now be readily comprehended. The flame-bed being easily removed and replaced by taking up the fire-bricks and supporting-girders, the boiler may be easily inspected and repaired, and the flame-bed being very thin—a feature rendered possible by this construction—causes the air to be highly heated before its entrance to the ash-pit, where it is distributed to the grate-surface and allowed to pass up the flues *d* into the expansion-chambers, the parts by having a constant circulation of air around them being rendered practically indestructible, and the air supplied to the front of the ash-pit being also heated to a high degree while circulating through the fire-door casing.

Having thus described my invention, what I claim as new is—

1. In a steam-boiler setting, the combination, with the bridge-wall and the air-passages for supplying air to the top thereof, formed by the metal bottom plates having the upwardly-extending webs or flanges, and the refractory blocks lying on the top of such

webs, of hollow perforated fire-bricks located over the mouths of such passages for distributing the air, substantially as described. 65

2. In a steam-boiler furnace, the combination, with the bridge-wall, of air-passages for supplying air to the top thereof, formed by the bottom plate having the upwardly-extending 7c webs, and the refractory blocks lying on the tops of such webs, substantially as described.

3. In a steam-boiler furnace, the combination, with the bridge-wall, of the passages for supplying air to the top of the same, formed 75 by the plates having the upwardly-extending webs with flanged tops, and the refractory blocks resting on such tops, substantially as described.

4. In a steam-boiler furnace, the combination, with the grate-bar, end bar, and bridge-wall, of the plates having the upwardly-extending webs, with the refractory blocks on such webs, forming air-passages for supplying air to the top of the bridge-wall and supported in position by the end bar, substantially as described. 85

5. In a steam-boiler furnace, the combination, with the grate, end bar, and bridge-wall, of the bottom plates having the upwardly-extending 9c webs with the flanged tops and the refractory blocks resting on such tops, the bottom plates and refractory blocks resting upon and supported by the end bar, substantially as described. 95

6. In a steam-boiler furnace, the combination, with the grate-bars, bridge-wall, and plates forming the air-passages, of an end bar having the two rails for supporting the grate-bars and plates forming the air-passages, respectively, the connecting-webs, and the apertures through which the air passes to the top of the bridge-wall, substantially as described. 100

7. In a steam-boiler setting, the combination, with the boiler, the setting-walls, and the supplemental walls or ledges on each side at the bottom, of the removable flame-bed underlying and in proximity to the boiler, formed of the girders lying loosely on said supplemental walls or ledges, and the refractory blocks removably supported on said girders, substantially as described. 105 110 115

8. In a steam-boiler furnace, the combination, with the grate, rear air-supply, and setting-walls having the projections or ledges, of a flame-bed overlying said air-passage for heating the air therein, formed of the T-shaped girders removably supported on the projections or ledges, with the flanges down and exposed to the air beneath, and the refractory 120 blocks removably supported on said flanges, substantially as described. 125
